UNITED STATES PATENT OFFICE.

MILON J. TRUMBLE, OF ALHAMBRA, CALIFORNIA.

VAPORIZER.

Application filed February 18, 1919. Serial No. 277,882.

To all whom it may concern:

Be it known that I, MILON J. TRUMBLE, a citizen of the United States, residing at Alhambra, in the county of Los Angeles and State of California, have invented a new and useful Vaporizer, of which the following is a specification:

My invention relates to vaporizers used with internal combustion engines, such as 10 are used on automobiles, and more particularly to means for preparing an explosive mixture such as is used in such engines.

The object of the invention is to provide a vaporizer by which low grade fuels such as 15 heavy distillates or kerosene may be utilized for the production of such explosive mixtures.

A further object of the invention is to provide means for returning to the fuel reservoir 20 any portion of the fuel which may be carried over in the mixture and which would otherwise pass in a liquid state into the engine thus causing lubrication and ignition troubles.

25 Referring to the drawing, which is for illustrative purposes only,

Fig. 1 is a view partly in section showing the method of connecting my invention to an internal combustion engine.

30 Fig. 2 is a section on an enlarged scale through the center of the vaporizer.

Fig. 3 is a section on a plane represented by the line 3—3 of Fig. 2.

35 Fig. 4 is a plan view partly in section showing the type of the fuel transfer valve used.

In the form of the invention illustrated in this drawing, 11 is a jacket provided with a tight cover 12 and open at the bottom. Secured in air tight relationship to the cover 40 12 is a fuel pan 13 forming with the cover 12 a fuel chamber 14. Also secured to the cover 12 but spaced therefrom by spacers 15 is an air pan 16. Secured to the air pan 16 is a case 17 and a shell 18. The case 17 is provided with a tight bottom 19 in which a central tube 20 is tightly secured. Also secured to the central tube is a baffle bottom 21 to which a cylindrical baffle 22 is secured, the baffle 22 extending concentrically up between the shell 18 and the case 17 to a point near the top thereof. Also secured to the central tube 20 and the shell 18 is a shell bottom 23. Resting on the shell bottom 23 is a deflector 24 having a tight deflector top 25. The deflector top 25 extends over the edges

of the cylindrical deflector 24 and is serrated to form small openings 26 as well shown in Fig. 3, for the purpose of spacing the deflector 24 from the shell 18. The lower edge 60 of the deflector 24 is also serrated to form small openings 27 as shown in Fig. 2.

Fitting loosely about the central tube 20 is an upper cone 30 and a lower cone 31, these cones being simply slipped over the tube 20 65 so that any liquid that may run down the outside of the tube or the surface of either cone can readily find its way between the tube 20 and the inner edges of the cones. The cones 30 and 31 are serrated at their upper edge to form small openings 32 and 33 as shown in Fig. 2.

The space between the jacket 11 and the case 17 may be termed an air preheating space 36, this preheating space being open 75 at the bottom so that air can readily pass therein and being in open communication at the top with the space between the fuel pan 13 and the air pan 16. The space between the case 17 and the shell 18 may be 80 termed the exhaust space 37, this space being divided into two parts by the baffle 22.

The exhaust space is connected into the manifold 40 of the internal combustion engine with which the invention is used by 85 means of a tube 41 which contains a heat control valve 42 so that the amount of exhaust gas passing into this space can be regulated by the operator by suitable valve operating mechanism not shown. The exhaust gases 90 pass outwardly through a tube 45.

Connected into the shell bottom 23, passing through the deflector bottom 21 and the bottom 19 is a drain pipe 46, this drain pipe communicating with the bottom of a pump 95 cylinder 47 through a check valve 48. A piston 49 slides in the pump cylinder 47 and a tube 50 having a check valve 51 therein connects the bottom of the cylinder 47 with the fuel chamber 14. The piston 49 is operated through a piston rod 52 from a bell crank 53 secured to a pin 54, this bell crank being operated manually through a throttle control rod 55 which is connected to the throttle lever, not shown, of the automobile. The pin 54 is connected to a throttle valve 56 in the central tube 20, which is connected through a flange 57 with the intake manifold 105 of the engine (not shown).

Located in the fuel chamber 14 is a float 110 60 which is pivoted on a pin 61 and which operates a needle valve 62 in a valve casting

68 closing the needle valve 62 whenever the fuel in the fuel chamber 14 reaches a predetermined height and opening this valve and replenishing the fuel in the fuel chamber 5 14 whenever the level of the fuel in this chamber falls sufficiently to make this necessary, thus maintaining a constant supply of fuel in the fuel chamber 14.

An opening 64 closed by the valve 62 communicates with a cavity 65 which is connected to a pipe 66 connected to a gasoline supply not shown and to a pipe 67 connected to a kerosene supply, not shown. Balls 68 operated by a cam 69 serve to shut off the 15 flow of liquid through either the pipe 66 or the pipe 67 at the will of the operator by suitable manual control mechanism not shown.

Secured in the cover 12 is a fuel head 70, 20 this fuel head having a hot air cavity 71 in the top thereof, the top of which is closed by a plug 72. The hot air cavity 71 is fed with hot air through a pipe 73, this pipe 73 extending through the center of the manifold 25 40 and being open to the air at 74 as shown in Fig. 1 so that when the engine is running a supply of hot air may be drawn there- 30 through. An opening in the lower portion of the hot air cavity 71 is closed by a nozzle 35 75 which is threaded therein so that it can be readily adjusted up or down.

Surrounding the nozzle 75 is an annular fuel chamber 76 in open communication with the fuel in the fuel chamber 14 and which 35 communicates through small openings 77 with a central opening 78 in the nozzle 75. This central opening 78 is conical and a stem 80 is seated therein. A series of hot air openings 81 are drilled in the bottom of 40 the hot air chamber 71, communicating with an opening 82 formed in the bottom of the fuel head 70. Sliding loosely in this opening 82 is a tube 90 having a skirt 91. The skirt 91 has a lip 92 which is turned down- 45 wardly and which is serrated to form a plurality of very small openings 93. The skirt 91 is secured in spaced relationship with a valve 94 which is of the proper shape and size to form a tight closure with the bottom 50 of the air pan 16. The air pan 16 has an opening 96 which is closed by the skirt 91 with the parts in the position shown in Fig. 2. The stem 80 is also secured in the valve 94, extending downwardly into a 55 socket 100 carried by the deflector top 25 in which a compression spring 101 is placed. This compression spring tends to hold the stem 80, the valve 94 and the skirt 91 in their upper position as shown in Fig. 2.

60 The method of operation of the invention is as follows:

The parts being in the position shown in Fig. 2 and the fuel chamber 14 being filled with gasoline which is ordinarily assured 65 by the operator of the engine turning on the

gasoline just before the engine is shut down, the engine is started by means of any auxiliary type of starter or by hand, thus causing a partial vacuum inside the central tube 20 which is connected to the intake of the 70 engine. The amount of this partial vacuum depends on the speed of the engine and acts upon the valve 94, tending to pull it down- 75 wardly from its seat on the air pan 16, and also pulling the stem 80 away from its seat in the nozzle 75. A partial vacuum acts through the central opening 78 on the cavity 76 which is in open communication with the fuel chamber 14, drawing fuel downwardly into the opening 82. This fuel is spread out by the skirt 91 and broken up by the small perforations 93, passing through the space between the fuel pan 13 and the air valve 94. Air is at the same time drawn up- 80 wardly through the preheating space 36 into 85 the space between the fuel pan 13 and the air pan 16, this air passing through the opening 96 into the space between the air pan 16 and the valve 94. In the latter space it mixes with the fuel which is being drawn 90 in a plurality of fine jets through the opening 93.

The mixture of air and fuel passes down- 95 wardly between the deflector cylinder 24 and the shell 18 and upwardly through the small openings 32 and 33, passing eventually into the central tube 20 from which it passes into the cylinders of the engine. This explosive mixture is then ignited and the engine starts to turn over under its own power, the 100 exhaust gases being discharged into the ex- 105 haust manifold 40. The exhaust gases heat the air which is passing through the opening 71 into the tube 73, the hot air passing into the hot air chamber 71 and downwardly through the small openings 81 into the space 82. This highly heated air tends to heat up the entire fuel head 70 and the fuel in the fuel chamber 14 therearound. It also mixes 110 with the vapor in the chamber 82 and passes with that vapor over into the central tube 20.

As soon as the engine is again heated up the eccentric 69 is thrown over to admit the heavier fuel such as kerosene to the fuel chamber 14. This heavy fuel is drawn into 115 the space 82 in which it is mixed with the hot air from the tube 73 and with hot air from the preheating space 36, the air in the space 36 having been heated by its contact with the heated case 17. The case 17 and 120 the shell 18 are heated by the exhaust of the engine passing through the tube 41 and controlled in amount by the valve 42. As a result hot air is supplied both through the tube 73 and from the preheating space 36. 125 This hot air heats the heavy fuel, helping to vaporize it and to produce an explosive mixture. This explosive mixture passes down- 130 wardly through the space between the shell 18 and the deflector 24 and through the open-

ings 27 into the interior of the deflector 24. In its passage downwardly through the thin annular space between the shell 18 and the deflector 24 the air and fuel are further heated, producing a further vaporization thereof, the heated mixture rising through the openings 32 and 33 into the space under the deflector top 25 and passing from this into the central tube 20 from which the mixture readily passes to the engine.

The deflector 24 and the deflector top 25 form a large heated chamber through which the mixture moves at a slow rate of speed. Any particles of unvaporized fuel tend to settle out in this chamber, this settlement being assisted by the upper cone 30 and the lower cone 31 which tend to collect any drops of unvaporized liquid, these drops running downwardly to the shell bottom 23. As this shell bottom is heated by the exhaust gases of the engine a certain portion of the liquid which settles thereon is further vaporized. Certain portions thereof are not vaporized and these portions tend to run down the tube 46 into the cylinder 47. The piston 49 being connected to the throttle rod 55, it is moved up or down whenever the throttle valve 56, which controls the speed of the engine, is operated.

When the engine is running under uniform conditions, in other words, when it is on the road at a more or less uniform speed there is not much tendency for unvaporized fuel to collect, this tendency being most marked during the times that the engine is being started or stopped frequently as happens when passing through a crowded city or when getting started on a trip. At these times the throttle is frequently manipulated and the excess fuel is readily pumped back into the fuel chamber 14. If at any other time the operator notices any accumulation of unvaporized fuel which can often be detected by an irregular operation of the engine, it is possible for him to pump this accumulation out by manipulating the hand throttle.

What I claim is:—

1. A vaporizer for producing an explosive mixture of air with the heated vapors of heavy hydrocarbons for use with an internal combustion engine, comprising an atomizing device for producing a finely divided mist from a supply of said heavy hydrocarbons, a heater for heating a primary air supply, a pipe for conducting said primary air into said atomizer in such a position that said air is mixed directly with said mist thus heating and vaporizing said mist, walls forming a passage through which a secondary air supply is drawn, members so placed as to mix said secondary air with the mixture of primary air and hydrocarbons, walls forming a precipitating chamber of large area into which said mixture is passed and

in which any unvaporized portions of hydrocarbon may settle, a tube connected to the intake manifold of said internal combustion engine, said tube being so situated that it can withdraw the mixture from near the top of said chamber, and a pump for forcing any liquid precipitated in said chamber back into said supply of heavy hydrocarbon.

2. A vaporizer for producing an explosive mixture of air with the heated vapors of heavy hydrocarbons for use with an internal combustion engine, comprising an atomizing device for producing a finely divided mist from a supply of said heavy hydrocarbons, a heater for heating a primary air supply, a pipe for conducting said primary air into said atomizer in such a position that said air is mixed directly with said mist thus heating and vaporizing said mist, walls forming a passage through which a secondary air supply is drawn, members associated with said walls to form an exhaust space, pipes connecting said exhaust space with the exhaust manifold of said engine, members so placed as to mix said secondary air with the mixture of primary air and hydrocarbons, walls forming a precipitating chamber of large area into which said mixture is passed and in which any unvaporized portions of hydrocarbon may settle, a tube connected to the intake manifold of said internal combustion engine, said tube being so situated that it can withdraw the mixture from near the top of said chamber, and a pump for forcing any liquid precipitated in said chamber back into said supply of heavy hydrocarbon.

3. A vaporizer for producing an explosive mixture of air with the heated vapors of heavy hydrocarbons for use with an internal combustion engine, comprising an atomizing device for producing a finely divided mist from a supply of said heavy hydrocarbons, a heater for heating a primary air supply, a pipe for conducting said primary air into said atomizer in such a position that said air is mixed directly with said mist thus heating and vaporizing said mist, walls forming a passage through which a secondary air supply is drawn, members so placed as to mix said secondary air with the mixture of primary air and hydrocarbons, walls forming a precipitating chamber of large area into which said mixture is passed and in which any unvaporized portions of hydrocarbon may settle, elements associated with the walls of said precipitating chamber to form a precipitating chamber heating space, means for passing the exhaust gases from said internal combustion engine through said precipitating chamber heating space, a tube connected to the intake manifold of said internal combustion engine, said tube being so situated that it can

- withdraw the mixture from near the top of said chamber, and a pump for forcing any liquid precipitated in said chamber back into said supply of heavy hydrocarbon.
- 5 4. A vaporizer for producing an explosive mixture of air with the heated vapors of heavy hydrocarbons for use with an internal combustion engine, comprising an atomizing device for producing a finely divided mist from a supply of said heavy hydrocarbons, a heater for heating a primary air supply, a pipe for conducting said primary air into said atomizer in such a position that said air is mixed directly with said mist thus heating and vaporizing said mist, walls forming a passage through which a secondary air supply is drawn, members so placed as to mix said secondary air with the mixture of primary air and hydrocarbons, walls forming a precipitating chamber of large area into which said mixture is passed and in which any unvaporized portions of hydrocarbon may settle, a tube connected to the intake manifold of said internal combustion engine, said tube being so situated that it can withdraw the mixture from near the top of said chamber, a throttle valve for controlling the flow of mixture, a pump having its suction side connected into the bottom of said precipitating chamber and its pressure side connected into said supply of heavy hydrocarbon, and mechanism connecting said pump with said throttle valve.
- 10 5. In a vaporizer, a fuel chamber in which a supply of liquid fuel is carried, a vaporizer fed from said fuel chamber and so arranged as to produce an explosive mixture of air and fuel, walls forming a precipitating chamber in which liquid is precipitated, a throttle valve arranged to control the flow of said mixture, a pump arranged to pump said liquid from said precipitating chamber into said fuel chamber, and mechanism connecting said throttle to said pump.
- 15 In testimony wherof, I have hereunto set my hand at Los Angeles, California, this 10th day of February, 1919.
